UNITED STATES PATENT OFFICE.

ALBERT FAUCK, OF KLECZANY, GALICIA, AUSTRIA-HUNGARY.

BORING-TOOL OR DETENT-TERRIER FOR OIL-WELLS, &c.

SPECIFICATION forming part of Letters Patent No. 299,632, dated June 3, 1884.

Application filed March 5, 1884. (No model.)

To all whom it may concern:

Be it known that I, ALBERT FAUCK, a citizen of the United States, residing at Kleczany, Galicia, Empire of Austria-Hungary, have invented 5 certain new and useful Improvements in Boring-Tools or Detent-Terriers for Oil-Wells, &c., of which the following is a specification.

This invention relates to an improved automatic boring-instrument of the class known 10 under the name of "detent-terriers," which instrument is specially adapted for boring to greater depth for water, petroleum, and other purposes; and the invention consists of a guide-frame, a slotted guide-sleeve, a boring-tool 15 secured to a detent-piece, and an automatically-working detent and releasing device, which will be more fully set forth hereinafter.

In the accompanying drawings, Figures 1 and 2 represent two different side views of my 20 improved automatic boring-tool, and Figs. 3 and 4 are details of the detent device.

Similar letters of reference indicate corresponding parts.

The boring-tool *a* carries at its lower end 25 the bit *b*, and is connected to the detent-piece *c* by means of two keys, *a'* *a''*. The detent-piece *c* is guided in its movement by the longitudinally-slotted sleeve *d*. This arrangement secures a great solidity of the apparatus, 30 and enables the different parts of the same to be readily taken apart. The sleeve *d* carries at its upper end a rod, *e*, of square section, which is guided by the head *f* of a guide-frame, *g g*. The upper end of the rod *e* is provided 35 with a screw for connection with a socket of the boring-rod or steel-wire rope. This connection is well known and not represented in the drawings. The guide-frame *g g* is composed of two side rails, which are fixed to the head *f*, and of a strong ring, *i*, that connects 40 the lower part of the side rails. The guide-frame *g g* serves as a guide for the boring-tool *a*, and as a base for the automatic detent device. The detent-piece *c* is provided near 45 its upper end with an upper transverse and slightly-oscillating cross-piece, *c'*, and with a lower fixed cross-piece, *c''*. (Shown in detail in Figs. 3 and 4.) Both cross-pieces *c' c''* are guided by the longitudinal slots *d'* of the sleeve *d*, 50 the upper cross-piece, *c'*, being made of greater length than the lower cross-piece, *c''*. The upper cross-piece, *c'*, turns by center pivots

in steel bearings *h h*, which are secured into transverse holes of the detent-piece *c* by conically-tapering keys *h' h''*. As the cross-piece 55 *c'* has to be secured to the detent-piece after it has been inserted into the sleeve *d*, the keys *h'* are introduced through suitable holes at the lower end of the sleeve, and retained in place by the sleeve itself. The upper ends *d'* of the 60 guide-slots *d'* are inclined and made wider than the slots *d''*, so as to form a seat, *d''*, for the upper cross-piece, *c'*. The head *f* of the sleeve *d* is provided with fixed downwardly-extending rails *K K*, the lower ends of which 65 are inclined, as shown in Fig. 1.

When the boring-tool is at work, the frame *g g* is resting upon the bottom of the bore-hole. Upon the descent of the boring-rod, the upper inclined ends *d'* of the guide-slots 70 *d'* of the sleeve *d* engage the upper cross-piece, *c'*, and turn the same, so that on the ascent of the boring-rod the cross-piece *c'* is taken along by the seat *d''* of the sleeve *d*. When the boring-bit during its ascent has 75 reached nearly its highest point, the inclined ends of the fixed rails *K K* push the upper cross-piece, *c'*, off its seat, so that the boring-tool and its detent-piece *c* are dropped.

The guide-frame *g g* should be longer than 80 the boring-tool (inclusive of the suspended piece) by the length of the stroke of the bit minus about six centimeters, so that the guide-frame is taken along a short distance after the detent-piece has fallen, so as to facilitate the 85 turning of the tool.

The apparatus works as well without water and without rebound of the walking-beam.

The above-described detent apparatus secures a reliable working of the boring-tool, 90 which is best effected by a stroke of 1.25 meter and with twenty to thirty blows per minute.

Having thus described my invention, I claim as new and desire to secure by Letters Patent—

1. The combination of a guide-frame, *g g*, 95 having fixed rails *K K*, inclined at the ends, a slotted sleeve, *d*, having a square rod, *e*, a detent-piece, *c*, carrying the boring-tool *a*, the detent-piece *c* having a longer oscillating cross-piece, *c'*, and a fixed lower cross-piece, *c''*, the 100 cross-piece *c'* being engaged by the rails *K* and automatically disengaged by the same during the ascent of the boring-tool, substantially as set forth.

2. The combination of a guide-frame, *g g*, having fixed rails *K K*, with inclined ends, a sleeve, *d*, having a fixed rod, *e*, and longitudinal guide-slots *d'*, with inclined upper ends *d'* and seats *d'*, a detent-piece, *c*, carrying the boring-tool *a*, and having a transverse longer oscillating cross-piece, *c'*, and a fixed shorter cross-piece, *c'*, substantially as and for the purpose set forth.
- 10 3. In detent-terriers, the combination of the detent-piece *c*, having an oscillating cross-piece, *c'*, with rails *K*, having inclined ends, said rails being fixed to the head of the guide-frame *g g*, substantially as described.
- 15 4. The combination of the boring-tool *a* with the detent-piece *c* by means of a double key, *a' a'*, which facilitates the taking apart of the different parts of the apparatus, substantially as described.
5. In detent-terriers, a guide-frame composed of side rails, a head, and a connecting-ring at the lower part of the side rails, substantially as set forth.
6. In detent-terriers, the detent-piece *c*, having a fixed lower cross-piece, *c''*, and an upper longer cross-piece, *c'*, that is centrally pivoted to transverse steel bearings *h h*, secured by wedge-keys *h' h'*, substantially as set forth.
- In testimony that I claim the foregoing as my invention I have signed my name in presence of two subscribing witnesses.

ALBERT FAUCK.
